UNITED STATES PATENT OFFICE.

JACOB FINE, OF LOUISVILLE, KENTUCKY.

APPARATUS FOR APPLYING FASTENERS.

1,355,457.

Specification of Letters Patent. Patented Oct. 12, 1920.

Application filed December 6, 1919. Serial No. 342,926.

To all whom it may concern:

Be it known that I, JACOB FINE, a citizen of the United States, residing at Louisville, in the county of Jefferson and State of Kentucky, have invented certain new and useful Improvements in Apparatus for Applying Fasteners, of which the following is a specification.

The implement or machine which is the subject of the present application for patent has been designed for applying cloth or other labels to caps, etc., by means of the holder or fastening device disclosed in Patent No. 1,316,779, issued September 23, 1919. Ordinarily, the labels, tags or the like on the inside of cloth and other caps are attached by being sewed on, whereas the patented fastening device is a thin sheet metal disk having outstanding spurs on both sides, which are so arranged that the spurs on one side may be driven into the cap or other article, whereas the label, tag or other article is applied by being impaled on the spurs on the other side. The invention has for its object to provide a simple, rapid and efficient implement for applying the fastening devices, and to this end it consists in a novel combination and arrangement of parts to be hereinafter described and claimed.

In order that the invention may be better understood, reference is had to the accompanying drawings forming a part of this specification, and while the preferred embodiment of the invention has been disclosed, it will be understood that various changes, and modifications may be made without a departure from the spirit and scope of the invention as claimed hereinafter.

In the drawings:

Figure 1 is a plan view of the machine with certain parts broken away; Fig. 2 is an elevation with parts broken away; Fig. 3 is an enlarged elevation of a detail, partly in section; Fig. 4 is a bottom plan view of the machine; Fig. 5 is a section on the line 5—5 of Fig. 2; Fig. 6 is a section on the line 6—6 of Fig. 1, and Figs. 7 and 8 are sections on the lines 7—7 and 8—8, respectively, of Fig. 3.

Referring specifically to the drawings, 10 denotes a base or table which carries the various elements of the implement, and is provided with supporting legs or feet 10a. 55 From the base rises a standard 11 having at

the top a support 11a for a vertically reciprocating stem 12 carrying at its lower end a plunger 13, and provided with a rack 14. A pinion 15 is in mesh with the rack 14, whereby the stem 12 is reciprocated to operate 60 the plunger 13. The pinion 15 is on a shaft 16 supported in a suitable bearing on the standard 11, and provided with an operating handle 17. A spiral spring 18 is connected to the shaft 16 in such a manner that 65 it turns the same in a direction to impart an upward or return stroke to the plunger stem 13 through the pinion 15 and the rack 14, the working stroke being in the opposite direction, or downward.

The function of the plunger 13 is to affix the fastening devices disclosed in the Patent No. 1,316,779 hereinbefore referred to. These devices are small sheet metal disks 19 having a pair of outstanding pliable spurs 70 20 on one side, and another pair of such spurs 21 on the other side. The disks are connected in the form of a strip as shown in Fig. 3. In fastening the label, tag or the like to the cap or other part, one or more 75 disks are first affixed to the cap, on the inside thereof, by one set of spurs, and the label is then impaled on the other set of spurs. The implement is shown equipped for the simultaneous application of four 80 disks, this being the number usually required to affix the label, but the structure may be modified to operate on any other 85 number of disks.

Each strip of disks is mounted in a suitable magazine 22 carried by a slidable guide and carrier 23 for the strip. The magazine is made fast to one end of the carrier 23, and on the other end is a standard 24 supporting a vertically slidable driver bar 25. The carrier 23 has a guide channel 26 for the strip of disks, extending from the outlet of the magazine 22 and terminating beneath the driver bar 25, so that one disk after the other may be projected and brought beneath the latter to be operated on in a manner to be presently described.

The driver bar 25 has a guide flange 25a at its rear edge, and the front face of the standard 24 has a slot to seat the bar and its flange. The bottom of the bar is flat and its rear flanged edge forms a shearing edge 25b adapted to come between the exposed disk and the next one behind the same to sever the former from the strip. The slotted por- 105 110

tion of the standard in which the driver bar works projects beyond the end of the guide channel 26 from which the disk to be severed projects, whereby a second shearing edge 25^c 5 is produced below the disk and in line with the edge 25^b, to coöperate therewith.

The driver bar 25 operates a device for feeding the strip of disks forwardly a distance to project one disk after the other to 10 be operated on. This feed device comprises the following parts:

From the back of the driver bar 25, through a slot in the standard 24, extends an arm 27 having at its outer end a cam edge 27^a. To a post 28 rising from the member 23 is pivoted, intermediate its ends, a lever 28^a, the pivot being shown at 28^b. One end of this lever has an abutment 29 20 in the form of a roller which is engageable by the cam surface 27^a. The other end of the lever carries a feed pawl 30, the same being pivoted to the lever, as shown at 30^a. The feed pawl may be in the form of a fork so as to come between two adjacent disks. 25 The post 28 also supports a spring, one end 31 of which presses upwardly against the arm 27 to elevate the driver bar 25, and the other end 31^a presses against the lever 28^a to swing the same in a direction giving 30 the pawl 30 its return stroke.

When the driver bar 25 starts to go down to sever a disk from the strip, the cam surface 27^a presses against the roller 29 and the lever 28^a then swings in a direction to give the pawl 30 its forward or working stroke, this stroke being completed before the end of the working stroke of the driver bar, so that a disk is now projecting and ready to be severed as the driver bar completes its working stroke. The feed movement of the pawl is completed as the roller 29 clears the cam surface 27^a. When the driver bar 25 makes its upward or return stroke, the spring end 31 swings the lever 45 28^a in a direction to again bring the roller 29 under the cam surface 27^a, and to give the pawl 30 its return stroke.

The driver bar 25 affixes the disk to the cap by pressing the spurs 20 thereinto, these 50 spurs being at the bottom. In order that the driver bar may clear the top spurs 21, it is recessed on opposite sides as shown at 32.

The cap to which the label is to be applied is placed on an anvil 33 at the center 55 of the table 10 and directly beneath the plunger 13.

The driver bars 25 are simultaneously operated in the manner hereinbefore described 60 by the plunger 13, and after the disks are applied to the cap, the label is placed on top of the disks, and the plunger 13 is again lowered to impale the label on the top spurs or spurs 21, the members 23 being first 65 swung to carry the driver bar 25 clear of

the anvil 33, so that when the plunger descends it comes directly in contact with the label and the disks.

The following means are provided for swinging or retracting the members 23. 70

Each member 23 is held by a set screw 34 in an undercut groove in the top of a block 35, the member 23 having a dovetailed bottom rib 35^a seating in said groove. This construction permits adjustment of the 75 member 23 to properly locate the driver bar 25 relative to the anvil 33. The block 35 is pivoted to a post 36 rising from the table or base 10, and on the pivot 37 is a sector gear 38 meshing with a similar gear 39 pivoted to the post 36, as shown at 39^a and extending downwardly through a slot 40 in the table. At the center of the table 10, on the under side thereof, is journaled, as shown at 41, a disk 42 connected by a rod 80 or link 43 to the lower end of the sector gear 39. The disk 42 has an operating handle 44. The swinging support of each member 23 has its sector gear 39 connected by a rod or link to the disk 42, and hence when 90 the latter is rotated, all of said members swing together. The pivots 37 are horizontal, and hence the members 23 may be swung upwardly to clear the anvil 33.

In order that two diametrically opposite 95 ones of the members 23 may be placed in various positions to adapt the implement to labels of different shapes necessitating a different grouping of the disks 19, the following devices are provided:

Two diametrically opposite posts 36 carry a pivoted arcuate bar 45, and the latter supports the block 35, said block however not being pivoted. The bar 45 is operated by a sector gearing in the same manner and for 105 the same purpose as the other blocks 35 which are pivoted directly to the posts 36. The bars 45 are curved on an arc having for its center the center of the table 10, and as the blocks 35 seating on said bars are 110 slidable thereon, said blocks can be slid toward and from the other blocks for the purpose hereinbefore set forth, they being held in adjusted position by set screws 46. The anvil may be made rotatable, with a center 115 depression to receive a button on top of the cap at the center.

I claim—

1. In a machine for applying fasteners consisting of disk-like members having projecting top and bottom spurs, an anvil, a driver engageable with the disk to impale the bottom spurs, and having its disk-engaging end shaped to clear the top spurs, a plunger for actuating the driver and also 120 engageable with the disk to impale the top spurs, and a support for the driver movable to take the same clear of the plunger.

2. In a machine for applying fasteners consisting of disk-like members having pro- 110

jecting top and bottom spurs, an anvil, a driver engageable with the disk to impale the bottom spurs, and having its disk-engaging end shaped to clear the top spurs, a 5 plunger for actuating the driver and also engageable with the disk to impale the top spurs, a support for the driver movable to take the same clear of the plunger, and disk-feeding means controlled by the driver.

10 3. In a machine for applying fasteners consisting of disk-like members having projecting top and bottom spurs, an anvil, a driver engageable with the disk to impale the bottom spurs, and having its disk-engaging end shaped to clear the top spurs, a 15 plunger for actuating the driver and also engageable with the disk to impale the top spurs, a pivoted support for the driver, and means for swinging said support to take the 20 driver clear of the plunger.

4. In a machine for applying fasteners consisting of disk-like members having projecting top and bottom spurs, and united in the form of a strip, an anvil, a driver engageable with a disk to impale the bottom spurs and also having means to sever the disk from the strip, the disk-engaging end of the driver being shaped to clear the top spurs, a plunger for actuating the driver 25 and also engageable with the disk to impale the top spurs, and a support for the driver movable to take the same clear of the plunger.

5. In a machine for applying fasteners consisting of disk-like members having projecting top and bottom spurs, and united in the form of a strip, an anvil, a driver engageable with a disk to impale the bottom spurs and also having means to sever the 30 disk from the strip, the disk-engaging end of the driver being shaped to clear the top spurs, a plunger for actuating the driver and also engageable with the disk to impale the top spurs, a support for the driver movable to take the same clear of the plunger, and means for feeding the strip.

6. In a machine for applying fasteners consisting of disk-like members having projecting top and bottom spurs, and united in 45 the form of a strip, an anvil, a driver engageable with a disk to impale the bottom

spurs and also having means to sever the disk from the strip, the disk-engaging end of the driver being shaped to clear the top spurs, a plunger for actuating the driver and also engageable with the disk to impale the top spurs, a support for the driver movable to take the same clear of the plunger, and means controlled by the driver for feeding the strips. 55

7. In a machine for applying fasteners consisting of disk-like members having projecting top and bottom spurs, and united in the form of a strip, an anvil, a driver engageable with a disk to impale the bottom spurs and also having means to sever the disk from the strip, the disk-engaging end of the driver being shaped to clear the top spurs, a plunger for actuating the driver and also engageable with the disk to impale 60 the top spurs, a support for the driver movable to take the same clear of the plunger, a lever carried by the support, a feed pawl for the strip carried by the lever, and an actuating arm for the lever on the driver. 65

8. In a machine for applying fasteners consisting of disk-like members having projecting top and bottom spurs, an anvil, a plurality of drivers each of which is engageable with a disk to impale the bottom spurs and has its disk-engaging end shaped to clear the top spurs, a plunger for operating the drivers and also engageable with the disks to impale the top spurs, and a support for the drivers movable to take the 80 same clear of the plunger. 85

9. In a machine for applying fasteners consisting of disk-like members having projecting top and bottom spurs, an anvil, a plurality of drivers each of which is engageable with a disk to impale the bottom spurs and has its disk-engaging end shaped to clear the top spurs, a plunger for operating the drivers and also engageable with the disks to impale the top spurs, and a support 90 for the drivers movable to take the same clear of the plunger, certain of said supports being adjustable to vary the grouping of the drivers. 95

In testimony whereof I affix my signature. 100

JACOB FINE.
